HYDROCARBON CONVERSION PROCESS

Carl J. Helmers, Bartlesville, Okla., assignor to
 Phillips Petroleum Company, a corporation of
 Delaware

Application May 27, 1943, Serial No. 488,757

1 Claim. (Cl. 196—52)

1

This invention relates to the catalytic treatment of hydrocarbon oils to produce lower boiling products including gasoline. In one of its more specific aspects, the invention embodies an improved process for the catalytic cracking of hydrocarbon oils to produce gasoline, wherein improved gasoline yields are obtained by segregation of fresh feed and/or recycle stocks according to optimum response to cracking conditions in two or more independently controlled catalytic treating zones.

It is the primary object of the instant invention to obtain improved yields of hydrocarbons boiling within the gasoline range by the cracking of hydrocarbon oils in the presence of suitable catalyst material.

Another important object of my invention is the more complete catalytic conversion of hydrocarbon oils to other hydrocarbons of preferred composition and high quality than has been economically feasible heretofore.

This invention has for a further important object the catalytic cracking of hydrocarbon gas oil in a manner whereby gasoline boiling range hydrocarbons of enhanced antiknock characteristics are produced economically and efficiently.

In the catalytic cracking of hydrocarbon oils of the nature of gas oil to produce maximum yields of high octane gasoline, the optimum per pass conversion is ordinarily limited by factors which vary with the relative depth of conversion. These factors include the quality of the gasoline product, the loss to fixed gases, and the amount of carbon deposited on the catalyst. The latter two are of particular importance from an economic standpoint as affecting process yields and the frequency and length of catalyst reactivation periods. In most cases, therefore, the per pass conversion is adjusted to give an economic balance between increased gasoline production and operating costs, with values of from about 25 to about 50 per cent conversion often selected for various feed stocks.

The production of additional amounts of gasoline of similar quality from unconverted feed stock may involve further treatment by recycling arrangements. The recycling of unconverted material to the original catalytic zone, however, is often unsatisfactory because of the decreased response of the once-treated oil to the original cracking conditions and a resultant decrease in overall conversion. For this reason, simple recycling of unconverted material may result in reduced process efficiency.

It has been proposed to pass total unconverted feed stock to one or more successive stages of

5 catalytic treatment at progressively more severe cracking conditions in order to maintain the per pass conversion. Such an operation, however, may result in products of decreasing quality as the treating conditions become more drastic, as well as lowered gasoline yields from more expensive operation. Other procedures included passage of the more refractory cycle stock to thermal cracking units where conversion is effected to a generally lower quality gasoline product but with less difficulty from coke and tar formation.

10 It has now been discovered that the increased refractory characteristics of catalytically cracked cycle gas oil stocks are due in large part to the formation and, under conventional recycling conditions, the rapid pyramiding of a relatively narrow-boiling fraction within the ordinary gas oil boiling range. This intermediate fraction is characterized by relatively low gravity for its 15 boiling range and much greater refractoriness than the higher boiling gas oil and lower boiling naphtha fractions.

15 I have also found that the building up of the quantities of this refractory fraction in the feed stock to catalytic cracking through a recycling operation reduces proportionately the per pass conversion at optimum conversion conditions. On the other hand, when conversion is maintained by altering conditions, there are uneconomic 20 losses to gas and coke of the less refractory components of both fresh feed and recycle oil.

25 I have additionally discovered that improved operation of a catalytic cracking system and higher product quality are obtained by a relatively complete segregation of the refractory light 30 gas oil fraction as it appears in fresh feed stocks and/or as it is formed in recycle gas oil stocks. The process steps which achieve this segregation and further accomplish efficient conversion to high octane gasoline are described hereinafter.

35 In one specific embodiment the invention comprises the following steps: (1) a suitable gas oil feed is catalytically cracked in a first cracking zone to produce partial conversion to gasoline and lighter products; (2) the reaction products are continuously fractionated to separate heavy, intermediate and light fractions all higher boiling 40 than the desired gasoline end point while the gasoline and lighter products are removed as products of the process; (3) the relatively narrow boiling range intermediate fraction of the unconverted gas oil is passed in suitable quantities to a second separate catalytic cracking zone to effect partial conversion to gasoline with the conversion products being passed to the fractionation and/or recovery system provided for the first

catalytic cracking zone (4) the heavy fraction of the unconverted gas oil is recycled in the desired proportions to the first catalytic zone along with fresh feed stock; (5) the naphtha fraction boiling between the gasoline end point and the light gas oil fraction is recycled to the first catalytic zone along with the heavy recycle stock.

These as well as other process steps are illustrated on the annexed drawing which is a diagrammatic representation of a suitable arrangement of process equipment. In the drawing, gas oil feed entering by a line 1 is preheated in a furnace 2, admixed with suitable diluent, such as superheated steam from a line 3, and further heated to conversion temperature. The vapors then pass through a line 4 to a catalytic reactor 5. Suitable conversion conditions are maintained in the reactor, and further quantities of superheated steam may be added as a heat carrier during conversion, as required.

The effluent from the reactor flows through a line 6 to a separator 7 where tar may be removed through a line 8. The vapors then pass through a line 9 to a column 10 which is the first section of the gas oil fractionating equipment. From the bottom of column 10 a stream of heavy gas oil is withdrawn through a line 11 while uncondensed material passes overhead through a line 12 to a second column 13. This latter column is operated to separate gasoline vapors from higher boiling oil. The bottoms product, a light gas oil fraction, is removed through a line 14, while a lower boiling naphtha cut may also be removed as a side stream from the column through a line 15.

The gasoline vapors passing overhead in column 13 are condensed in passing through a line 16 to an accumulator 17 from which water may be withdrawn through a line 18. The hydrocarbon condensate is stabilized in column 19 by separation of light gases overhead through a line 20. The stabilized gasoline passes through a line 21 to a unit 22 for clay treatment (or its equivalent) before being sent to storage.

The light gas oil cut which is obtained as the bottoms product of column 13 is passed through a line 23 as charge stock to the second catalytic treatment. In this second cracking step the oil is preheated in a furnace 24 and passes through a line 25 to a reactor 26. Superheated steam may be added from a line 27 to the oil vapors either before or during the catalytic treatment. Other suitable diluents may be employed with or without steam with proper adjustment of treating conditions and/or separation steps. Such diluents may include light refractory hydrocarbon gases or hydrogen-containing recycle gases from the process or from associated operation. The effluent from reactor 26 passes through lines 28 and 29 to the fractionating system of the first catalytic step where it may enter ahead of separator 7. The gas oil and gasoline products of the second catalytic step are thus recovered along with products of the first cracking step.

In some cases, due to special properties or uses of the gasoline and/or gases produced in the second step (as described hereinafter) the second step effluent may wholly or partially be passed to a separate fractionating system through a line 30.

The heavy gas oil fraction according to the drawing is wholly or partially recycled through line 11 to the gas oil charge line 1 to the first catalytic step. Uncycled heavy oil may be withdrawn through a line 34 or the volume and end point of recycle material controlled by control

of the temperature in the separator 7. In a similar manner a portion of the light gas oil in line 14 may be withdrawn through a line 33 to avoid accumulation of material too refractory to crack satisfactorily. The boiling range of the light gas oil is effectively controlled by the temperature at the top of column 10 and the location of the side stream indicated by line 15 on column 13. While a single fractionating unit is indicated by column 13, this fractionation may be done in a plurality of separate columns, if desired.

Many alternative operations and modifications are possible in carrying out the process illustrated by the flow diagram. While no attempt will be made to discuss all such modifications, two alternative operations are of particular interest in connection with the illustrated operations. First, the fresh gas oil feed instead of passing to the pre-heating furnace of the first catalytic cracking step may pass first to the fractionating system for separation into the different boiling ranges. This is indicated by a line 31 through which a full range gas oil charge may pass (after preheating if desirable) on the fractionating system which it enters ahead of the separator 7.

The second modification comprises a preliminary fractionation of an original wide boiling range gas oil charge in suitable fractionating equipment (not shown) so that fresh feed streams of light and heavy gas oil and naphtha may be passed directly to the respective catalytic cracking steps either in a once-through operation or along with recycle stocks separated as described above from the catalytic conversion products.

Obviously, various types of conventional equipment may be utilized in the process to accomplish the above described conversion, fractionation and other steps. Various types of catalytic reactors may be employed, particularly in the first catalytic step wherein the less refractory stocks are treated under usually milder conditions. The reactor may be any suitable type other than the fixed bed chamber illustrated, such as multitubular reactors, moving catalyst reactors and the like. In the second cracking step, a fixed bed reactor with provisions for the injection of a heat carrier diluent is often preferred because of the relatively higher temperatures and/or pressures employed and the fact that some other types of reactors have temperature and pressure limitations of a mechanical nature.

In the practice of this invention on a wide variety of gas oil stocks from different sources, the first catalytic cracking treatment is ordinarily carried out at temperatures in the range of about 800 to about 1100° F., depending on the catalyst employed, the reaction time and the desired per pass conversion. The pressures are usually low superatmospheric pressures of about 15 to about 500 pounds gage and flow rates may range from about 1 to 10 barrels of oil per ton of catalyst per hour. The catalysts employed are those known as suitable for cracking of heavy hydrocarbons, such as natural clays, bauxite, brucite, activated clays or silicates, synthetic alumina and/or magnesia preparations promoted with various metal oxides, synthetic silica-alumina compositions, or the like.

The second catalytic treatment to which the light refractory gas oil is charged is usually carried out at somewhat higher temperatures than the first step, for example, in the range of about 950 to about 1300° F. The type and activity of the catalyst employed as well as other conditions such as the reaction time and the proportions of

diluent employed will in many cases determine the optimum conversion temperature.

In comparative terms, the refractory gas oil fraction requires higher cracking temperatures and/or longer contact time and less dilution with steam or other diluent than the less refractory stocks at the same conversion level. For example, when employing the same catalyst of moderate activity in both catalytic steps to produce maximum quantities of gasoline, the second step may be carried out at temperatures about 50 to 100° F. above the temperatures in the first step, with reduced proportions of steam diluent, or even in the absence of a diluent.

In certain instances, the light refractory gas oil may be treated under conditions of temperature, pressure and contact time which produce deep conversion to valuable normally gaseous products and proportionately reduced yields of gasoline. The refractory nature and low coke forming tendency of the stock make possible conversion in the temperature range of 1100-1300° F. without uneconomic formation of carbon and fixed gases so that reactions favored by such high temperatures may be carried out. In the high temperature-low pressure conversion steps, principal products may be light olefins (ethylene, propylene and butylenes), butadiene, C₅ diolefins and highly aromatic gasoline which may be utilized in aviation gasoline. When the light gas oil is treated under those conditions, the products of the second catalytic step are ordinarily passed to separate fractionation equipment for segregation of the above described special products. The unconverted gas oil may be recycled but is often withdrawn since per pass conversion may range from about 50 to about 80 weight per cent of the oil charged.

The behavior of the light refractory gas oil fraction and the circumstances under which it is built up in the unconverted portion of a full range gas oil indicate that this fraction contains relatively large proportions of cyclic hydrocarbons. This is further substantiated by the relatively low A. P. I. gravity for the observed boiling range and the extensive cracking and/or dehydrogenation to form high octane aromatic type gasoline when sufficiently high temperatures are reached.

While the exact limits of the boiling range which includes the total refractory fraction may vary somewhat with such factors as the source, previous treatment and the precision of previous fractionation of a gas oil stock, the principal portion of the refractory material ordinarily boils between about 475 and 575° F. Still higher concentrations of refractory material may often be obtained by closer fractionation to a boiling range of about 490 to about 550° F., but in most operations the wider boiling range is entirely satisfactory for the separation of the light refractory gas oil cut.

The lower boiling naphtha, e. g., boiling between about 400 and about 475° F. is less refractory and is usually converted to gasoline in satisfactory yields under relatively mild cracking and/or dehydrogenation conditions. Similarly, the heavy gas oil fraction boiling between about 575 to about 725° F. or higher may be relatively easily converted to lower boiling products comprising gasoline, gases and a substantial proportion of material in the above described refractory boiling range of about 475 to 575° F. This formation of refractory stock from the heavy gas oil fractions causes the rapid increase in the propor-

tions of the refractory fraction under ordinary direct recycling conditions.

In many cases the octane ratings and yields of gasoline produced by catalytic cracking of the heavy gas oil stocks are highest when the reaction time is relatively short and the length of the process period is limited. Thus, in treating heavy gas oil fractions over bauxite catalyst at temperatures in the neighborhood of 975 to 1000° F. moderate pressures and relatively high proportions of steam or other diluents are beneficial; and the optimum process period may be in the range of about 1 to 3 hours. These conditions produce suitable per pass conversion and aid in the maintenance of catalyst activity by suppression of carbon formation.

In contrast, the treatment of the light refractory gas oil stocks under similar conditions may accomplish per pass conversion substantially below an economic optimum. These refractory stocks respond to catalytic processing with relatively long reaction times; hence, conditions may include elevated pressures, lower charge rates and/or smaller proportions of diluents. The refractory gas oil stocks are usually less susceptible to carbon formation and the process periods may often be extended to six hours or more without substantial depreciation in gasoline quality, even though a relatively deep per pass conversion is obtained.

Furthermore, the light refractory gas oil stocks produce gasoline products of substantially higher octane rating under conventional catalytic cracking conditions, and this quality may, if desired, be utilized to advantage by the segregation methods of the present invention. For example, the relatively narrow boiling range refractory stock may be subjected to special conversion treatments wherein the predominant concentration of cyclic hydrocarbons and relatively high carbon-hydrogen ratio are utilized in the production of aromatic gasoline stocks or other products of specialized uses.

From the foregoing discussion it will be seen that the different fractions of gas oil or recycle stocks employed in catalytic cracking are utilized with improved efficiency according to the process of the present invention. The following exemplary operations will further illustrate the process methods and advantages of this invention but since many modifications are possible within the scope of the disclosure, no limitation to the specific stocks, treating conditions or products of said examples is intended.

Example I

A gas oil cut from West Texas crude oil had the following characteristics:

Gravity _____ A. P. I. 35.6
Boiling range _____ °F. 505 to 762
Volume per cent in fraction 475-575° F. 16

This stock was catalytically cracked by passage over bauxite catalyst at 960° F. average catalyst temperature, 75 pounds gage pressure, and a flow rate of about 6 barrels per ton of catalyst per hour. The oil was admixed with steam ahead of the catalyst to produce a steam-oil mol ratio of 14:1. The per pass conversion to products boiling below 400° F. was about 25 weight per cent of the oil charged, and the principal product was butane-free gasoline of about .78 octane number.

The recycle gas oil from this first pass operation had the following characteristics:

Gravity ..... °A. P. I. 35.2
 Boiling range ..... °F. 460-748
 Volume per cent in fraction 475-575° F. 36

A second-pass cracking operation on this recycle stock under substantially the same conditions gave a per pass conversion, only about 60 per cent of the first pass conversion, with the octane rating of the butane-free gasoline slightly lower than that of the first pass gasoline. The gas oil residuum from the second pass treatment contained 50 volume per cent of the fraction boiling between 475 and 575° F. so that a third pass treatment at the original condition was impractical.

Example II

A full range Mid Continent gas oil was cracked over bauxite catalyst at an average catalyst temperature of 985° F., 35 pounds gage pressure and a flow rate of 8 barrels per ton of catalyst per hour. Steam was admixed with the oil charge prior to and during the catalytic treatment in an oil-steam weight ratio of 2:1. The optimum process period was about 3 hours while carbon deposits amounted to about 1 weight per cent of the oil charged. Conversion per pass was 35 weight per cent of the oil charged and the butane-free gasoline had an ASTM octane rating of 78.

The fresh feed and recycle stocks had the following characteristics:

	Fresh feed	Recycle
Gravity..... °A. P. I.	36.0	34.5
Boiling range..... °F.	450-750	450-700
Vol. percent of fraction 475-575° F.	38	60

Recycling of the unconverted gas oil from the first pass operation reduced the per pass conversion to about 22 weight per cent of the oil charged, and when conditions were altered to increase the per pass conversion to the level of 30-35 per cent, the carbon deposition increased to about 3 weight per cent of the oil charged and process period length was reduced.

The recycle stock was then fractionated to separate two recycle streams with the following characteristics:

	Light recycle	Heavy recycle
Gravity..... °A. P. I.	37.0	31.5
Boiling range..... °F.	450-620	550-740
Vol. percent in fraction 475-575° F.	75	2

The heavy recycle stock was returned to the original catalytic treatment along with an intermediate naphtha fraction boiling between about 400 and 450° F. and original conversion conditions were substantially maintained.

The light recycle stock was charged to a separate cracking unit where it was admixed with steam in an oil-steam weight ratio of 5:1 and passed over bauxite catalyst at an average catalyst temperature of 1010° F. and a flow rate of 6 barrels per hour per ton of catalyst. The per pass conversion was 40 weight per cent of the oil charged during a six hour process period and the corresponding gasoline yield was 34 weight per cent. The gasoline after stabilization to remove C₄ and lighter material had ASTM and Research octane numbers of 80 and 92, respectively.

Example III

A full range Mid Continent gas oil similar to that of Example II was given a preliminary fractionation to produce light and heavy stocks.

5 These stocks were treated over bauxite catalyst under substantially identical cracking conditions at a temperature of 960° F. and a reaction time of 5 seconds. The following comparative results were obtained in three hour process periods with 10 steam-oil mol ratios in the charge of about 8:1.

		Light gas oil	Heavy gas oil
15	Charge characteristics:		
Gravity..... °A. P. I.	38	31	
Boiling range..... °F.	450-635	540-740	
Vol. percent in fraction 475-575° F.	62	1	
Per pass conversion, wt. percent of charge.	18	30	
Octane rating of B. F. gasoline (A. S. T. M.)	79	77	
20	Residuum characteristics:		
Gravity..... °A. P. I.	37.1	30.1	
Boiling range..... °F.	467-637	450-740	
Vol. percent in fraction 475-575° F.	65	30	

A second pass treatment at the same conditions of the unconverted heavy gas oil stock increased 25 the refractory portion boiling between 475 and 575° F. to 42 volume per cent, while the per pass conversion dropped to about 20 per cent.

The unconverted gas oil from the cracking of the heavy gas oil was then fractionated to produce light and heavy recycle stocks, with the light recycle stock added to the fresh feed light gas oil and the heavy recycle stock returned with fresh feed heavy gas oil and the intermediate naphtha cut.

30 The catalytic treatment of the heavy stock was continued at approximately the original conditions to produce 30-40 per cent per pass conversion during a three hour process period. The

40 light gas oil stock was treated in 6 hour process periods at a catalyst temperature of 985° F. The steam-oil mol ratio was reduced to 2:1 and the reaction time increased to 15 equivalent seconds at 960° F. The per pass conversion was 41 weight 45 per cent of the gas oil charged with a gasoline yield of about 85 volume per cent of the gas oil converted. The butane-free gasoline had ASTM and Research octane ratings of 78 and 90, respectively.

Example IV

A light gas oil stock containing about 75 volume per cent of material in the 475 to 575° F. boiling range was segregated from fresh-feed and recycle stocks in a catalytic cracking operation. This refractory stock was cracked by passage over bauxite catalyst at an average catalyst temperature of 985° F. and 75 pounds gage pressure without addition of steam. Conversion per pass was about 38 weight per cent of the oil charged, and carbon deposition was less than one per cent on the same basis. The process period was 6 hours.

Example V

65 The light gas oil stock of Example IV was cracked by passage over bauxite catalyst at an average catalyst temperature of 1175° F., 6 pounds gage pressure and a contact time of 0.8 second. The steam-oil mol ratio was 9:1. About 70 80 weight per cent of the oil charged was converted to gasoline and light gases including large yields of ethylene, propylene and butylenes, and 75 butadiene equivalent to about 2 weight per cent of the oil charged. The gasoline yield was about 30 weight per cent of the oil charged and was

highly aromatic. The fraction boiling between 150 and 350° F. had an ASTM octane number of 89 and was segregated for treatment and employed as aviation gasoline stock.

I claim:

A process for the catalytic conversion of hydrocarbon gas oil to gasoline which comprises catalytically cracking a stream of gas oil in first cracking step at a temperature in the range of about 800 to 1,100° F., fractionating the effluents thereof to thereby obtain a plurality of hydrocarbon fractions comprising a first heavy fraction substantially boiling at a temperature above about 575° F., a second intermediate relatively refractory fraction substantially boiling within the temperature range of about 475 to 575° F., a third less refractory fraction substantially boiling within a temperature range of about 400 to 475° F., and a fourth fraction within the gasoline boiling range; recycling said first and third fractions to said first cracking step, catalytically cracking said second fraction in a second cata-

lytic cracking step under more drastic cracking conditions than said first step at a temperature in the range of about 950 to 1,300° F., and fractionating the effluents of said second catalytic cracking step to obtain therefrom a fraction boiling within the gasoline range.
